UNITED STATES PATENT OFFICE.

CLARE H. DRAPER, OF HOPEDALE, MASSACHUSETTS, ASSIGNOR TO HOPEDALE MANUFACTURING COMPANY, OF MILFORD, MASSACHUSETTS, A CORPORATION OF MASSACHUSETTS.

WEFT-REPLENISHING LOOM.

Application filed July 7, 1925. Serial No. 42,012.

The present invention relates to an improvement in weft replenishing looms and more particularly in looms of the rotary magazine type known as rotary hopper looms. The hopper as heretofore constructed has sometimes given rise to the breakage of the thread extending from the end of the bobbin to the thread plate by reason of the winding of the thread on the bobbin tip when the bobbin was forced into the shuttle by the transfferer hammer.

The object of this invention is to produce a construction of bobbin tip holder which will prevent the winding of the thread on the tip of the bobbin when the bobbin is discharged from the hopper and forced into the shuttle, and to this end the present invention consists in the weft replenishing loom hereinafter described and particularly defined in the claims.

In the accompanying drawings illustrating the preferred form of the invention, Fig. 1 is a part of a sectional elevation of the hopper of a weft replenishing loom; Fig. 2 is a front view of the small-end disk showing the bobbin holders in position therein; Fig. 3 is a plan and Fig. 4 is a rear elevation of the bobbin tip holder; and Fig. 5 is a sectional elevation of the same.

The hopper plate 1 carries the hopper which comprises the butt end disk 2 and the small-end disk 3. Also secured on the hopper is the thread disk 4 over which the end of the yarn from the bobbin is extended to the thread holder 5. The bobbin is supported in the hopper by having its butt inserted in a recess in the outer face of the butt end disk and by having its tip received in a tip holder 6 carried by the small-end disk. The tip holder is a casting having an inner end 7 hooked over the flange 8 of the small-end disk. This end 7 is inserted through a slot 9 in the small-end disk, and the tip holder is normally pressed toward the bobbin by the tip holder spring 10 which is received at one end in a spring seat 11 in the small-end disk and at the other end in a spring seat 12 in the tip holder. The outer end of the tip holder is provided with a tip socket 13. Leading to the tip socket is a tip groove 14. Beyond the tip groove the tip holder is provided with a thread groove 15, and on each side of the thread groove are thread directing surfaces 16 and 17. The bobbin 18 is inserted in the hopper

by thrusting its butt end into a recess in the butt end disk and then forcing its tip down against the tip groove 14, which when pressed upon by the tip of the bobbin causes the tip holder to rock on its pivot on the flange 8 away from the butt end disk so as to permit the bobbin tip to pass the high point 19 of the tip groove 14. As soon as the tip passes beyond the high point the tip holder is pressed toward the butt end disk and holds the bobbin in the tip socket 13. The two thread directing surfaces 16 and 17 operate to guide the thread into the thread groove 15 and control the thread as the bobbin is removed from the hopper and forced into the shuttle. The thread 20 extending from the bobbin tip to the thread disk is loosely held in the hand as the bobbin is inserted in the hopper and is then drawn out over the edge of the thread disk and wound around the thread holder 5. It extends from the thread groove to the thread disk on a diagonal line, as shown in Fig. 3, and the thread directing surface 17 is so formed, as shown, that it causes the thread always to be entered into the thread groove; then when the bobbin is forced out of the hopper the tip moves through the tip groove with the thread extending, as shown in Fig. 3, from the side thereof such that the thread unwinds from the bobbin tip with the transfer movement. The thread directing surface 16 is a plain curved surface leading from the flat portion 21 down into the thread groove, as shown, but the thread directing surface 17 (opposite the off-set) is provided with a diagonal ridge 22 which causes the yarn to slide down into the thread groove. It will be observed that if the thread is laid up on the thread directing surface 17 in the position indicated in the broken line 23, the discharge movement of the bobbin might cause the thread to wind up on the bobbin tip 24 and thereby cause such a shortening of the yarn between the bobbin tip and the thread disk as to cause a breakage of the yarn. The presence of the ridge 22 prevents the thread from assuming any such position as that indicated at 23, in view of which the thread would wind up on the bobbin as the bobbin is discharged from the hopper.

It is to be noted that the thread groove 15 is offset from the center of the tip, as shown in Fig. 3, so that when the bobbin 18

tip leaves the tip holder 6 during transfer, the tip moves by the thread lying in the groove 15, with the result that new thread is supplied from the bobbin, i. e., unwinds from the bobbin during transfer movement. Reference to Fig. 2 shows the groove 15 of a tip-holder 6 located a little to one side of the radius extending from the center of the hopper to the corresponding tip socket 13. 10 The position of the thread groove with respect to a radial line extending through the tip socket constitutes a feature of the invention.

The present invention contemplates, in its broader aspects, a construction in which the hopper is provided near the tip position with the peculiar thread groove and thread directing surfaces, irrespective of the particular thing upon which this groove and the 15 thread directing surfaces are formed.

What is claimed is:

1. A weft replenishing loom provided with a hopper having bobbin holders including a small-end disk provided with tip holders for receiving the tip of the bobbin, such tip holders having an outer end provided with a tip groove, an off-set thread groove leading to the tip groove and thread directing surfaces on opposite sides of the thread groove, 25 the thread directing surface opposite the off-set being provided with a diagonal thread guiding ridge to guide the thread into the thread groove so as to prevent the thread

from winding up on the bobbin tip as it is discharged from the hopper into the shuttle 35 at replenishment.

2. A weft replenishing loom provided with a hopper having bobbin holders including a small-end disk provided with tip holders for receiving the tip of the bobbin, the holders being provided adjacent to the tip position with an off-set thread groove leading to the tip position, and thread directing surfaces on opposite sides of the thread groove, the thread directing surface opposite the off-set 40 being provided with a diagonal thread guiding ridge to guide the thread into the thread groove so as to prevent the thread from winding up on the bobbin tip as it is discharged from the hopper into the shuttle 45 at replenishment.

3. A weft replenishing loom provided with a hopper having means for holding bobbins, such hopper being provided with an off-set thread groove leading to the tip position, 55 and thread directing surfaces on opposite sides of the thread groove, the thread directing surface opposite the off-set being provided with a diagonal thread guiding ridge to guide the thread into the thread groove 60 so as to prevent the thread from winding up on the bobbin tip as it is discharged from the hopper into the shuttle at replenishment.

In testimony whereof I have signed my name to this specification.

CLARE H. DRAPER.
